UNITED STATES PATENT OFFICE.

EZEKIAL FIELD WHITE, OF ATLANTA, GEORGIA.

CARBURETER.

979,907.

Specification of Letters Patent.

Patented Dec. 27, 1910.

Application filed May 19, 1909. Serial No. 496,996.

To all whom it may concern:

Be it known that I, EZEKIAL F. WHITE, a citizen of the United States, and a resident of Atlanta, in the county of Fulton and State of Georgia, have made certain new and useful Improvements in Carbureters, of which the following is a specification.

My invention is an improvement in carbureters, and consists in certain novel constructions, and combinations of parts hereinafter described and claimed.

The object of the invention is to provide a carbureter for positively feeding the liquid fuel, in a proper mixture, and which will vary the richness of the mixture inversely with relation to the speed, and without the use of small valves.

The drawing shows a longitudinal section of the improvement.

20 The present embodiment of the invention comprises a housing 1, which is provided with a plurality of ports, namely, a main air inlet 2, an auxiliary air inlet 3, an outlet 4 for the mixture, and an outlet or overflow 25 5 for the gasolene, a receptacle 6, being provided within the housing at one side thereof for receiving the gasolene.

The receptacle for the gasolene is separated from the body of the housing by a 30 partition wall 7 which extends nearly to the top of the housing, and the upper edge of the partition wall is rabbeted as at 8.

The mixture outlet 4 is separated from the main air inlet 2, by a partition wall 9, and 35 the inlet 2 is separated from the body of the housing by a partition wall 10, and the free edges of the said partition walls engage annular flanges 11 and 12 on a bushing 13, the flange 12 resting on the rabbeted edge 8 of 40 the partition wall 7, while the flange 11 engages the said wall. The upper end of the bushing is closed as at 15, and the side wall thereof is provided with a plurality of annular interrupted slots 20—21 and 22, and a 45 substantially cylindrical valve 14 is journaled in the bushing, and is provided with a plurality of annular interrupted slots 20^a, 21^a, and 22^a, which are adapted to register more or less with the slots of the bushing, in 50 accordance with the angular position of the valve with respect to the bushing. The slots when in register place the interior of the valve in communication with the ports 3, 4 and 2 respectively, and the position of the 55 valve is varied by a governor mechanism,

and also manually by mechanism to be presently described.

The lower end of the interior surface of the valve is provided with oppositely arranged longitudinal slots 23, in which are 60 slideable arms 24 on a bushing 25, journaled in a bearing in the lower end of the housing. The bushing 25 is provided with an annular groove 17 for receiving the bearing, and with a lateral flange 18 engaging the outer 65 face of the bearing, and a lever or handle 19 extends radially from the flange. It will be evident that by moving the lever the valve will be rotated, thus bringing the slots of the valve and the bushing 14 more or less in 70 register. The valve is also movable longitudinally with respect to the bushing, against the resistance of a spring 26, by means of governor, consisting of a pair of 75 balls 27, each of which is connected with one arm of an elbow lever 28, pivoted between a pair of ears 29 on a sleeve 30, which is provided with a reduced portion 31, received in a hub 32 in the upper end of the housing. The other arm of each elbow lever engages a 80 recess 33, in a collar 34, pinned to a shaft 35 by a pin 36, the shaft being journaled in the sleeve, and the lower end thereof being received in a hub 37, on a spider 38 within 85 the valve.

The lower face of the spider 38 is provided with a boss 39 which engages within one end of the coil spring 26 before mentioned, the lower end thereof being engaged by the end of a threaded rod 40, which is received within the threaded hub 41 of a hand wheel 42 journaled in the lower end of the bushing 25.

It will be evident from the description, 95 that when the balls are rotated above a predetermined speed, they will move outward by centrifugal force, thus depressing the rod which in turn depresses the valve, and brings the slots of the bushing and valve more or less out of register.

The point at which depression of the valve will commence may be varied by increasing or decreasing the tension of the spring. This may be done by turning the hand wheel 42. The rod 40 is guided in its movement by a disk 43 secured thereto and moving within the bushing 25, the edges of the disk being slotted to receive the arms 24.

The governor balls are rotated by means of a bevel gear wheel 44, secured to the 110

sleeve 31, and engaging a bevel gear 45, secured to a stud shaft 46, by means of a key 47, the stud shaft being journaled in a hub 48, in the side of the housing between the 5 ports 3 and 5. The outer end of the stud shaft has keyed thereto a pulley 49, which may be connected to the engine by a belt (not shown.)

The bevel gear 45, as will be evident from 10 an inspection of the drawings rotates partly in the receptacle 6 for gasoline, and between its hub 50 and the gear teeth, it is provided with a plurality of transverse openings 51, within each of which is arranged a pair of 15 spaced gauze partitions 52.

The auxiliary air inlet 3 is arranged exactly opposite the line of movement of the openings, and the gasoline is maintained at a fixed level on the receptacle by means of 20 the overflow pipe 5, which permits the surplus liquid to pass out.

An annular curtain 53 of gauze encircles the bushing adjacent to the slots 20 and 20^a, the curtain being secured to the under face 25 of the bevel gear wheel 44, and the lower edge of the curtain extends below the slots and sets close to the outer wall of the bushing.

The operation of the device is as follows: 30 As the gear wheel 45 rotates it dips into the gasoline, and a portion of the same is carried up on the gauze partitions of the openings. As the partitions pass the inlet 3, the current of air therethrough strikes the partitions and carry a portion of the gasoline therefrom toward the interior of the valve. The air laden with gasoline strikes the curtain 53, and since the said curtain is revolving, all surplus gasoline is thrown off, 40 thus effectually preventing the entrance of any liquid into the valve. The mixture which enters the valve is pure, and on its entrance into the valve it meets the current of air entering through the main port 2, and 45 the mixture is properly diluted passing to the explosion chamber through to the port 4. The current of air entering through the port 3 is preferably heated, and the curtain 53 forms an effective guard to prevent the 50 entrance of water or other foreign substances to the valve. Since the curtain is always damp with the gasoline the water will not adhere but is immediately thrown off.

It will be understood, that the proportion 55 of the mixture, is regulated by the lever 19 in the first instance, in accordance with the conditions to be met, and that the governor

is an auxiliary regulator for varying the proportion and the quantity in accordance with conditions incident to the running 60 of the engine, such as, for instance, an increase or decrease in speed.

It will be evident that an increase of speed will decrease the quantity of mixture admitted, while at the same time the proportion of gasoline in the mixture is decreased. The richness of the mixture is thus varied inversely with respect to the speed. This is done by the curtain 53, which will throw off more gasoline, the faster it 70 revolves. As the speed decreases from the above causes, the curtain throws off less gasoline and the mixture is enriched, while at the same time the amount of mixture admitted is increased.

It will be evident from a consideration of the drawing and description that all small valves are dispensed with, a single large valve controlling the device, thus eliminating a fruitful source of trouble.

I claim—

1. In a carbureter, a bushing provided with annular interrupted slots forming ports for the purpose set forth, a valve rotatable therein and having similar slots for registering therewith, said valve being longitudinally movable, manually operated means for rotating the valve, a governor, a connection between the governor and the valve for moving it longitudinally, a curtain encircling 90 the bushing in front of the inlet port, means for revolving the curtain around the bushing, a receptacle for gasoline, a bevel gear for driving the governor and dipping into the receptacle, said gear rotating in front 95 of the inlet port, and a connection between the gear and the curtain for operating the same.

2. In a carbureter, a housing having an air inlet, a valve rotatable therein and provided with an inlet for air and the liquid fuel, a receptacle for the liquid fuel, a gear wheel rotating on a horizontal axis and adapted to be driven by the engine and dipping into the receptacle, the portion of the gear above the axis passing between the air inlet and the inlet of the valve, a screen movable between the gear wheel and the inlet of the valve, and a governor operated by the gear wheel.

EZEKIAL FIELD WHITE.
